LIFE PRESERVER

Henry A. Goldsmith, Dayton, Ohio

Application November 13, 1946, Serial No. 709,631

1. Claim. (Cl. 9—17)

(Granted under the act of March 3, 1883, as amended April 30, 1928; 370 O. G. 757)

1

The invention described herein may be manufactured and used by or for the Government for governmental purposes without payment to me of any royalty thereon.

This invention relates to life preservers and particularly to life preservers of the pneumatic type.

An object of the invention is to provide a pneumatic life preserver, the inflatable space of which is divided into separate compartments by bulkheads of relatively thin highly resilient material, such, for instance, as latex rubber sheeting with separate inflation means connected into the space on each side of the bulkhead, whereby, if either side, leaks or either inflation means fails to function, or in the event inflation is intentionally accomplished through one of the inflation means only, the inflation pressure will merely expand the bulkhead into the side which is not being inflated and the device will nevertheless be inflated to substantially full capacity.

Another object of the invention is to provide a life preserving device for persons subjected to drowning hazards which may be secured to the body and worn in the deflated condition as part of their standard equipment without discomfort and without interfering with their normal duties.

Another object of the invention is to so shape and proportion the several parts of the device that when it is inflated and in the water it will right itself from any position and support the wearer in a slightly reclining posture with his head on a comfortable head rest well above the water, irrespective of the type of clothing being worn and irrespective of whether the wearer is conscious or unconscious.

Another object is to provide as part of the structure, an inflatable collar, which when deflated, has a large, loose and comfortable neck opening, but which by inflation, is snugged more closely to the neck, whereby slipping of the wearer's head through the collar is avoided.

Another object is to join the front or open part of the collar to the frontal container in such a manner that inflation of the frontal container will form a chin rest at its upper end which will prevent face down flotation should unconsciousness overtake the wearer so that his head would slump forward.

Another object is to provide the device with a coating of fluorescent die of a bright hue whereby it will remain visible and distinguishable at distances at which normal colors remain black or are unseen.

Other objects and advantages will be become evident as the invention is further described with reference to the drawings.

Wherein,

Fig. 1 is a perspective view showing the bottom and the left side of the device when inflated, the left side carrying the automatic and oral inflation means and the bottom carrying the snap fasteners which are provided for holding the device in accordion shape when it is being worn deflated.

Fig. 2 is a perspective view showing the top and the right side of the device when inflated, the right side carrying a second set of inflation means like that shown in Fig. 1 and the top showing the collar and chin rest.

Fig. 3 is another perspective view showing the top and right side of the device with part of the collar and part of the frontal container broken away to show the bulkheads and the manner in which they must be joined to divide the inflatable space of the device into two parts, each part inflatable by its own set of inflation means.

Fig. 4 is a rear perspective view of the device showing the manner of attachment of the harness.

Figs. 5 and 6 are perspective views of the device when deflated and strapped to a user showing the collar collapsed and the frontal container folded up against the body.

Fig. 7 shows the device on a wearer after inflation has been accomplished showing how the device provides both a pillow for the wearer's comfort pending rescue and a chin rest to insure that his head will not slump forward should he become unconscious.

Like reference characters refer to like parts throughout the several views.

As shown in the drawings, the improved life preserver consists of two main units, a collar 10 and a frontal container 12, both preferably made of synthetic or natural rubber-coated nylon fabric, the collar being of more or less horseshoe shape with the open part of the horseshoe joined at 14 and 16 (see Figs. 1 and 2) to the frontal container near but not quite at, the upper end. It should be noted that the upper end surface 17, Fig. 2, of the frontal container 12 is so shaped that it bulges upward when inflated to form a chin rest for the wearer.

The space within the frontal container 12 is divided into two substantially equal compartments 18 and 20 (see Fig. 3) by a vertical bulkhead or diaphragm 22 of highly resilient material, preferably latex rubber sheeting or the like. The vertical bulkhead 22 at the upper end merges into a ring-like bulkhead 23 of like material which divides the space within the collar 10 into two chambers 24 and 26. Vertical bulkhead 22 and ringlike bulkhead 23 may be made up of a

number of pieces or may consist of a single piece as shown. In either event the parts 22 and 28 will constitute a single bulkhead and may be designated by the numeral 23. With the bulkhead 23 constructed and positioned as shown the circular chamber 24 of the collar and the compartment 20 of the frontal container merge at 30, while the circular chamber 26 and the compartment 18 merge at 32.

Chamber 24 and compartment 20, when connected together as one may be collectively referred to as the enclosure 21 while chamber 26 and compartment 18, when connected together as one, may be collectively referred to as the enclosure 19. Either one of the two enclosures 19 or 21 is of sufficient capacity when inflated to support the wearer with his head above water.

The automatic inflation means consists of two carbon dioxide cylinders contained in holders 34 and 34a fixed to the left and right side, respectively, of the frontal container 12, the holders being provided with lever means 36 and 36a actuatable manually by cords 38 and 38a to puncture the cylinders and allow the gas to escape into the inflatable cavities. The holder 34, Fig. 1, is so placed on the left side of the frontal container 12 that it discharges into the enclosure 19, while the holder 34a, Fig. 2, is so placed on the right side of the frontal container 12 that it discharges into the enclosure 21.

The oral inflation means is provided as a supplement to the automatic inflation means to replenish air supply which may be lost by leakage or as a substitute in case the automatic inflation fails. It consists of two flexible tubular members 40 and 40a with check valves 42 and 42a at the outer end biased for inflow of air and against return flow. The member 40, Fig. 1, is so placed on the left side of the front container 12 that it discharges into the enclosure 21, while the member 40a, Fig. 2, is so placed on the right side of the frontal container 12 that it discharges into the enclosure 19.

Secured to a tab 44 which depends from the back of the collar 10 is a harness which consists of two straps 46 preferably of nylon webbing about one and one-half inches wide and having a tensile strength of about eighteen hundred pounds per inch of width, attached to the tab 44 in the form of an inverted V. The free ends of the straps are brought around the body of the wearer and held in quick acting buckles 48 which are secured to tabs 50 near the lower end of the frontal container.

When the device is deflated and on the body of a wearer, the collar is a comfortable free fit around the wearer's neck and the front container may be folded up against the body in accordion fashion and held in that position by the snap fasteners 52, Fig. 1.

The use of the device may preferably be carried out substantially as follows:

Assuming that as a matter of precaution the device, in the deflated condition has been strapped to the body as seen in Figs. 5 and 6. In this condition the wearer may go about his work in comfort. The collar 10 now fits loosely, the frontal container 12 is collapsed in accordion fashion against the chest, and the chin rest bulge 17 is in the lowered position. If the need for a life preserver arises he may, either before or after he enters the water, pull the cords 38 and 38a which will pierce the carbon dioxide cartridges and inflate both enclosures 19 and 21 equally and automatically. As inflation pro-

ceeds and the frontal container 12 fills, the collar is brought up closer to the neck, the back of the collar rising to provide a head rest and the bulge 17 on the upper side of the frontal container 12 rising to provide a chin rest, as seen in Fig. 7. If rescue is delayed and slight leakage of the original inflation occurs, he may replenish the air supply through the oral means. If either enclosure 19 or 21 is punctured, or if the inflation means for either enclosure fails to function, additional inflation of the operative side will merely stretch and force the bulkhead over into the defective enclosure and thus correspondingly enlarge the undamaged side.

Having described an embodiment of my invention, I claim:

A pneumatic life preserver which comprises, in combination, an inflatable vertically disposed frontal container adapted, when deflated, to flatten up against the chest of the wearer, and having a bulgeable portion on the top surface of said frontal container, adapted, upon inflation to form a chin rest, an inflatable horizontally disposed horseshoe shaped collar having the open ends of the horseshoe connected into the right and left sides of the vertically disposed frontal container near the upper end thereof, the rear portion of the collar being widened to provide a pillow for the wearer when the collar is inflated, a continuous bulkhead of highly flexible sheet material extending vertically from right to left through the vertical container midway of its fore and aft walls, said continuous bulkhead then narrowing to a ribbon placed edgewise between the top and bottom walls of the collar midway between the outer and inner periphery of the collar, thereby dividing the space within the preserver into two substantially equal enclosures each composed of one of the two spaces within the frontal container and one of the two spaces within the collar and each of which, when inflated, is symmetrically disposed with respect to the body of the wearer, separate gas cartridge means for automatically inflating each enclosure, separate means for orally inflating each enclosure, whereby, when one enclosure becomes punctured or leaks from other causes, full inflation may nevertheless be achieved by introducing double the normal volume of air or other gas into the other, thereby forcing said bulkhead of highly flexible sheet material against the outer wall of the leaking enclosure, harness straps attached to the back of the collar, and quick acting buckles on the sides of the frontal container near the bottom thereof for receiving the free ends of said straps.

HENRY A. GOLDSMITH.
